(57) **CLAIM**

(**) Term: **14 Years**

The ornamental design for a dermatological optical delivery system, as shown and described.

(21) Appl. No.: **29/305,888**

DESCRIPTION

(22) Filed: **Mar. 28, 2008**

FIG. 1 is a perspective view showing the top, front side, and right side of a dermatological optical delivery system according to our new design;

(51) **LOC (9) Cl.** **24-01**

FIG. 2 is a perspective view showing the top, rear side, and left side thereof;

(52) **U.S. Cl.** **D24/172**

FIG. 3 is a front view thereof;

(58) **Field of Classification Search** D24/108,

FIG. 4 is a rear view thereof;

D24/133, 172, 186; 351/209–212, 206; 600/398–400,
600/402

FIG. 5 is a left side view thereof;

See application file for complete search history.

FIG. 6 is a right side view thereof;

(56) **References Cited**

FIG. 7 is a top view thereof; and,

U.S. PATENT DOCUMENTS

FIG. 8 is a bottom view thereof.
